(57) **CLAIM**

The ornamental design for a neckbag, as shown.

DESCRIPTION

FIG. 1 is a perspective view of the neckbag;

FIG. 2 is front elevation view thereof;

FIG. 3 is a right side view thereof (left being mirror image);

FIG. 4 is a top view thereof; and,

FIG. 5 is another perspective view thereof.

The broken line showing of the environment of the drawings is for illustrative purposes only and does not form part of the claimed design.
